(57) **CLAIM**

The ornamental design for an earphone case, as shown and described.

DESCRIPTION

FIG. 1 is a front perspective view of an earphone case, showing a first embodiment of our new design;

FIG. 2 is a front view thereof;

FIG. 3 is a back view thereof;

FIG. 4 is a top view thereof;

FIG. 5 is a bottom view thereof;

FIG. 6 is a right side view thereof;

FIG. 7 is a left side view thereof;

FIG. 8 is a back perspective view thereof;

FIG. 9 is a front perspective view thereof, shown in an environmental use;

FIG. 10 is a back perspective view thereof, shown in an environmental use;

FIG. 11 is a front perspective view of an earphone case, showing a second embodiment of our new design;

FIG. 12 is a front view thereof;

FIG. 13 is a back view thereof;

FIG. 14 is a top view thereof;

FIG. 15 is a bottom view thereof;

FIG. 16 is a right side view thereof;

FIG. 17 is a left side view thereof;

FIG. 18 is a back perspective view thereof;

FIG. 19 is a front perspective view thereof, shown in an environmental use; and,

FIG. 20 is a back perspective view thereof, shown in an environmental use.

The broken lines showing the earphones in FIGS. 9, 10, 19 and 20 depict the environment of the claimed design, and

(Continued)

form no part thereof. The remaining broken lines in drawings show portions of the earphone case that form no part of the claimed design.

1 Claim, 20 Drawing Sheets
